UNITED STATES PATENT OFFICE.

WILFRID G. CHAUSSE, OF DETROIT, MICHIGAN, ASSIGNOR TO CHAUSSE MANUFACTURING COMPANY, OF DETROIT, MICHIGAN, A CORPORATION OF MICHIGAN.

VAPOR-BURNER.

1,197,010.

Specification of Letters Patent.

Patented Sept. 5, 1916.

Application filed December 6, 1915. Serial No. 65,220.

To all whom it may concern:

Be it known that I, WILFRID G. CHAUSSE, a subject of the King of Great Britain and Ireland, residing at Detroit, in the county 5 of Wayne and State of Michigan, have invented certain new and useful Improvements in Vapor-Burners, of which the following is a specification.

This invention relates to improvements in 10 vapor-burners and particularly to that class of portable vapor-burners using hydro-carbon fuel, which are designed to give intense heat so as to be used as paint burners, heaters for soldering irons, and for brazing, 15 melting snow and ice from switch points and similar purposes.

In many of the structures of this class, in use at the present time, the means for feeding fuel from the fuel reservoir to the 20 burner proper is of such a nature that the usefulness of the burner is curtailed because if it is used in certain positions the fuel will not flow properly from the reservoir to the burner, and to work efficiently these burners 25 must be held in certain positions.

The objects of this invention are: First, to provide a device of this nature, comprising a fuel reservoir and burner, so connected that the fuel will always flow from the reservoir to the burner irrespective of the position in which the device is used. Second, to provide in a vapor-burner, an improved feeding device automatically actuated by 30 change in position of the fuel reservoir so as to open the fuel inlet of said feeding device which shall be lowermost at that position of the reservoir. Third, to provide in a vapor-burner a feeding device comprising a feed tube having a pair of fuel inlets and means 35 automatically actuated by a change in position of the reservoir, to open the lowermost fuel inlet and close the uppermost fuel inlet. Fourth, to provide in a vapor-burner a fuel feeding device comprising a feed tube 40 having a pair of fuel inlets, and automatic means operated by gravity for opening and closing said inlets, one or the other of said inlets being always open. Fifth, to provide in a vapor-burner a feeding device having a 45 pair of fuel inlets and automatic selective means for opening the fuel inlet nearest the lowest point in the fuel reservoir.

Further objects and objects relating to

economies of manufacture and details of construction will definitely appear from the 55 detailed description to follow.

I accomplish the objects of my invention by the devices and means described in the following specification.

The invention is clearly defined and 60 pointed out in the claims.

A structure constituting an embodiment of my invention is clearly illustrated in the accompanying drawings forming part of 65 this specification in which:

Figure I is a view in side elevation of a vapor-burner constructed in accordance with my invention, a part of the fuel reservoir being broken away to show the feed-tube. Fig. II is a longitudinal, sectional view 70 on the line 2—2 of Figs. III and IV. Fig. III is a transverse, sectional view through the feed tube on the line 3—3 of Figs. I and II. Fig. IV is a transverse, sectional view through the feed tube on the line 75 4—4 of Fig. II. Fig. V is a view in side elevation of a modified form of feed tube. Fig. VI is a longitudinal, sectional view of the modified form of feed tube, taken on the line 6—6 of Figs. VII and VIII. Fig. VII 80 is a transverse, sectional view on the line 7—7 of Figs. V and VI. Fig. VIII is a transverse sectional view on the line 8—8 of Figs. V and VI. Fig. IX is a view, in end elevation, of the modified form of feed 85 tube.

In the drawings, similar reference characters refer to similar parts throughout the several views, and the sectional views are taken looking in the direction of the little 90 arrows at the ends of the sectional lines.

Considering the numbered parts of the drawing, my improved vapor-burner comprises a fuel reservoir 1 and a burner proper which is designated generally by the numeral 2. The fuel reservoir is provided with an air pump 3 for supplying air pressure to the reservoir so as to force the fuel to the burner proper. A handle 4 is provided and legs 5 are secured to the cylindrical tank 100 or reservoir 1. The burner 2 is connected with the fuel reservoir by means of the pipe 6 in which there is a cut-off valve 7. The burner 2 comprises a tube 8 provided near its rear end with openings 9 for admitting 105 the proper amount of air for combustion.

These openings 9 may be closed partly or wholly by the sliding regulating shield 10 so as to control the amount of air admitted to the burner. Ears 11, extending downwardly 5 from the tube 8, support the pipe 6 which extends adjacent to the tube 8 so that the fuel is heated by the burner before it reaches its outlet in the burner. A receptacle 12 is provided in which a quantity of hydro-carbon 10 may be ignited to start the burner as is usual in burners of this type. A nipple 13 is threaded into the end wall of the fuel reservoir and the end of the pipe 6 is screwed into the nipple 13. A feed tube 14 extends 15 approximately the length of the reservoir, as shown in Fig. I, and one end of this feed tube 14 is threaded into the nipple 13.

In one form of my device, I use a feed tube constructed in accordance with Figs. II, 20 III, and IV. A plug 15 is screwed into the farther end of the feed tube and fuel inlet openings 16 and 17 are formed in the wall of said feed tube adjacent the ends thereof. A slide valve, comprising the flanged plungers 18 and 19 carrying the packing rings 20 25 and 21 and connected by rod 22, is disposed within the feed tube 14 with the packing rings 20 and 21 snugly engaging the wall of said feed tube. The length of the rod 22 is slightly greater than the distance between 30 the fuel inlet openings 16 and 17, so that, for example, when the packing ring 21 closes opening 17, the other packing ring 20 clears opening 16. A weight tube or cylinder 23 is 35 disposed within the feed tube 14 with the rod 22 extending through said cylinder as shown in Fig. II. This weight tube is shorter than rod 22 and is free to slide thereon, the ends of the said weight tube being 40 adapted to engage the plungers 18 and 19. A ring 24 is threaded into the end of the feed tube 14 which is screwed into the nipple 13, said ring serving to limit the movement of the slide valve.

In Figs. V to IX, I have shown another 45 form of feed tube which may be used in place of the feed tube shown in Figs. II, III, and IV. In this modification, the feed tube 25 is provided with the fuel inlet openings 26 and 27 adjacent the ends thereof. Valve seats 28 and 29 are formed on the side 50 of the tube 25 as shown in Figs. V, VI and VIII. Valves are provided closing the openings 26 and 27 and comprising the valve stems 30 and 31, having the heads 32 and 33, and packing 34 and 35 disposed around the stems and beneath the heads and normally seating on the valve seats 28 and 29. A leaf spring 36 is secured at its center to the 55 tube 25 at 37 and the ends of said spring engage the heads 32 and 33 so as to hold said valves normally closed. A bar 38 with pointed ends, is disposed within the feed tube 25 as shown in Fig. VI. The valve stems 30 and 31 extend through the open-

ings 26 and 27 and are adapted to be engaged by the pointed ends of the bar 38 as shown in Fig. VI.

From the description of the parts given above, the operation of my device should 70 be very readily understood. The hydro-carbon fuel in the reservoir 1 is forced under air pressure supplied by the pump 3, through pipe 6 to the burner 2. The fuel passes into pipe 6 through the feed tube 75 14. With the parts in the position shown in Figs. I and II, the fuel enters the feed tube 14 through the opening 16, flows the length of the feed tube and passes through the ring 24 into the pipe 6. If the apparatus 80 should be turned to a vertical position in which the reservoir 1 is uppermost and the burner 2 lowermost, the opening 16 would be above the level of the fuel and the fuel would not feed the burner. However, when 85 the apparatus is turned to such a position, the weight 23, in the feed tube 14, falls and engages the flanged plunger 19 moving the slide valve in the feed tube until the movement is limited by the stop ring 24 closing 90 inlet 16 and opening inlet 17, which is beneath the level of the fuel, so that the flow of fuel to the burner is uninterrupted. Similarly, if the torch should be turned to a position in which the burner 2 is above and 95 the reservoir 1 is below, the weight 23 would operate, in the feed tube 14, to move the slide valve to a position in which the inlet 17 is closed and the inlet 16, which would in 100 that case be below the fuel level, is opened. It will be seen that the slide valve in the feed tube 14 is automatically actuated, by a change in position of the apparatus, so as to open the inlet which is lowermost and hence below the level of the fuel in the reservoir. It will also be evident that one or 105 the other of the inlets will always be open. The result is that, by means of the use of my feeding device, the fuel will always be fed to the burner irrespective of the position 110 in which the apparatus is used. The other form of feed tube, which I have shown in Figs. V to IX inclusive, operates on the same principle. The leaf spring 36 tends to keep the valves closed. If the torch should be moved to a position in which the burner is below, the weight 38 moves in the feed tube 25 until it strikes the cross bar 39 of the stop ring 40. The pointed end of weight 115 38 engages the valve stem 31 and lifts the packing 35 away from the seat 29 opening the inlet 27. At the same time, the other pointed end of weight 38 moves out of engagement with valve stem 30 and the spring 36 forces the packing 34 against seat 28 closing the inlet 26. The movement of weight 38 is limited, in one direction by the plug 120 15, and, in the other direction, by the cross bar 39 of the stop ring 40. The extreme 125 length of weight 38 is equal to the distance 130

between the valve stems 30 and 31 so that one of the valves will always be open.

I am aware that the particular embodiments of my invention, which I have here shown and described, are susceptible of considerable variation without departing from the spirit of my invention, and, therefore, I do not wish to be restricted to the specific structures shown except as required by the appended claims. I have found, however, that these embodiments are desirable from many standpoints and, therefore, I wish to claim them specifically as well as broadly, as indicated by the appended claims.

Having fully described my invention, what I claim as new and desire to secure by Letters Patent is:

1. In an apparatus of the class described, the combination of a fuel reservoir, a burner, a removable feed tube extending into said reservoir and connected to said burner, said tube being provided with inlet openings adjacent the ends thereof; valves controlling the flow through said openings, a weight slidable in said tube to open the lowermost valve, and means actuated by the movement of said weight for positively closing the uppermost valve.

2. In an apparatus of the class described, the combination of a fuel reservoir, having an opening in the side thereof, a burner, a nipple screwed into said opening, a feed tube screwed into said nipple and provided with inlet openings adjacent the ends thereof, valve means controlling said inlet openings, a weight slidable in said feed tube to actuate said valve means, said feed tube and valve means being of less diameter than the opening in the side of said reservoir whereby the feed tube and valve means are removable therethrough.

3. In an apparatus of the class described, the combination of a fuel reservoir, a burner, a feed tube extending into said reservoir and connected to said burner, said feed tube being provided with inlet openings ad-

jacent the ends thereof, valves closing said inlet openings and provided with stems extending into said tube, a leaf spring secured to said tube with its ends engaging the heads of said valves, a weight slidable in said tube and provided with pointed ends, and stop means for limiting the movement of said weight, all coacting substantially as described and for the purpose specified.

4. In an apparatus of the class described, the combination of a fuel reservoir, a burner, a feed tube extending into said reservoir and connected to said burner, said feed tube being provided with inlet openings adjacent the ends thereof, valves closing said inlet openings and provided with stems extending into said tube, a leaf spring secured to said tube with its ends engaging the heads of said valves, and a weight slidable in said tube and provided with pointed ends.

5. In an apparatus of the class described, the combination of a fuel reservoir, a burner, a feed tube extending into said reservoir and connected to said burner, said feed tube being provided with inlet openings adjacent the ends thereof, valves closing said openings and provided with stems extending into said tube, spring means holding said valves normally closed, and a weight slidable in said tube to lift the lowermost valve against the tension of said spring means.

6. In an apparatus of the class described, the combination of a fuel reservoir, a burner, a feed tube extending into said reservoir and connected to said burner, said feed tube being provided with inlet openings adjacent the ends thereof, valves closing said inlet openings and provided with stems extending into said tube transversely thereof, and a weight slidable in said tube to engage the stem of the lowermost valve and lift the same.

In witness whereof, I have hereunto set my hand.

WILFRID G. CHAUSSE.
